UNITED STATES PATENT OFFICE.

HENRY S. BREWINGTON, OF BALTIMORE, MARYLAND.

GARMENT-CLASP.

SPECIFICATION forming part of Letters Patent No. 703,526, dated July 1, 1902.

Application filed October 31, 1901. Serial No. 80,685. (No model.)

To all whom it may concern:

Be it known that I, HENRY S. BREWINGTON, a citizen of the United States, residing at Baltimore city, in the State of Maryland, have 5 invented new and useful Improvements in Garment-Clasps, of which the following is a specification.

My invention relates to garment-clasps of the class especially adapted for use as waist-10 band-clasps for trousers.

The primary object of the invention is to provide a trousers clasp or fastening which will be so constructed as to insure a firm attachment to the garment and to supplement 15 the stitching by which this class of clasps are ordinarily secured by prongs engaging the garment in such a manner as to prevent undue strain upon the stitches.

The invention comprises two engaging 20 members of novel construction, as hereinafter fully described, and illustrated in the accompanying drawings, in which—

Figure 1 is an elevation of the hook member of the clasp. Fig. 2 is a similar view of 25 the bar or hasp member thereof. Fig. 3 is an edge view of the hook member. Fig. 4 is an edge view of the bar or hasp, and Fig. 5 is an elevation of a slightly-modified construction of the hook.

30 The reference-numeral 1 designates a plate of sheet metal bent upon itself to form a hook 2 and formed with a longitudinal slot 3. The plate is also formed with elongated slots 4 to form an outwardly-extending central prong 35 5 and two inwardly-projecting prongs 6. The point of the prong 5 projects beyond the points of the prongs 6, which is a feature of importance in insuring the firm attachment of the clasp. The plate 1 is provided with laterally-projecting perforated ears 7 to receive the threads or stitches which secure the plate to the garment and is formed with a transverse slot 8 at one end for the same purpose.

45 9 designates the bar or hasp member of the clasp, formed adjacent to each of its ends with a struck-up tongue 10 and bent transversely at right angles to form shoulders extending across the width of the bar and perforated ears 11, by means of which the bar is stitched 50 to the garment.

It will be noted that the tongues 10 project inward from the ends of the bar and serve as prongs to attach the same to the trousers.

The modified construction shown in Fig. 5 55 differs from that seen in Figs. 1 and 3 only in

the relative positions of the prongs 5^a and 6^a. In Fig. 5 the prongs 6^a are located a considerable distance from the central prong 5^a, while in Fig. 1 the prongs 6 are arranged closer to the central prong 5.

6c

The utility of the device will be readily understood.

The oppositely-projecting prongs engage the material of the garment and hold the hook member of the clasp from longitudinal 65 movement in either direction, and when the hook is secured by stitching it is firmly and reliably attached. The oppositely-disposed struck-up tongues or barbs of the hasp member also serve to prevent longitudinal movement thereof in either direction and provide an effective attaching means supplementing the securing threads or stitches.

70

The tongues or barbs of the hasp member are struck up from a point near the ends of 75 the hasp and extend inward directly from their point of attachment to the hasp, as distinguished from tongues struck up and bent inward, leaving openings which weaken the 80 securing ends of the hasp.

I claim—

1. A garment-clasp comprising a hook member consisting of a metallic plate bent upon itself to form a hook and slotted to form an outwardly-projecting central prong and inwardly-projecting prongs one on either side of the central prongs, and a bar or hasp member provided with oppositely-disposed struck-up tongues, and perforated ears. 85

2. A garment-clasp comprising a metallic 90 plate bent upon itself to form a hook, and slotted to form an outwardly-projecting central prong, and inwardly-projecting prongs one on either side of the central prong, and having laterally-projecting perforated ears. 95

3. A bar or hasp for a garment-clasp comprising a metallic plate bent transversely adjacent to its ends to form shoulders extending across the width of the bar, and said plate having attaching-ears and tongues struck up 100 from the metal and lying in the plane of said ears, the said tongues being attached at their outer ends to said ears and extending therefrom toward each other.

In testimony whereof I affix my signature 105 in presence of two witnesses.

HENRY S. BREWINGTON.
